ATTORNEYS

UNITED STATES PATENT OFFICE.

ZVETKO ORIZAROFF, OF HARRISBURG, PENNSYLVANIA.

PICTURE-HOLDER.

1,285,346.

Specification of Letters Patent. Patented Nov. 19, 1918.

Application filed April 27, 1918. Serial No. 231,138.

To all whom it may concern:

Be it known that I, ZVETKO ORIZAROFF, a citizen of the United States, and a resident of Harrisburg, in the county of Dauphin 5 and State of Pennsylvania, have invented a new and Improved Picture-Holder, of which the following is a full, clear, and exact description.

This invention relates to hangers or holders for picture frames, mirrors, ornamental panels, or the like, and has particular reference to holders or hangers of this character that are adapted to support the picture frame without cords, wires, screw eyes, or 15 the like, being attached thereto.

Another object of the invention is to provide a holder that is adapted to be connected to the side edges of the upper portion of the frame in such a manner as to be securely 20 held in place and so securely support the picture in practice.

With the foregoing and other objects in view the invention consists in the arrangement and combination of parts hereinafter 25 described and claimed, and while the invention is not restricted to the exact details of construction disclosed or suggested herein, still for the purpose of illustrating a practical embodiment thereof reference is had 30 to the accompanying drawings, in which like reference characters designate the same parts in the several views, and in which—

Figure 1 is a front elevation showing my 35 improved holder in coöperation with a picture or picture frame.

Fig. 2 is a side elevation of the same.

Fig. 3 is a plan view.

Fig. 4 is an enlarged detail of the supporting spur at the right side of the holder; and 40 Fig. 5 is a vertical sectional detail on the line 5—5 of Fig. 1.

Referring now more particularly to the drawings, I show at 10 a frame which will be understood to typify any device such as 45 a picture, mirror, or the like, to be supported as by hanging from a nail on the wall or the like or as an easel, the side rails 11 of the frame being provided with horizontal coaxial sockets 12 which may be lined if desired with metal bushings 13. These sockets 12 may be located at any desired elevation 50 along the sides of the picture.

The holder may be made of any suitable material such as sheet metal, celluloid, or the 55 like, that may be suitably ornamented or decorated as may be found desirable. As indi-

cated, however, the holder comprises two main portions 14 and 15 having a hollow rivet 16 connecting them and adapting the two main portions to pivot scissor fashion 60 not far remote from their upper ends.

Said upper ends 17 are provided with interlocking hooks 18 overlapping each other in a vertical direction, while the end portions above the hollow rivet 16 are curved 65 away from each other forming an eye or loop 19 adapted to be placed over a nail 20 or the like.

The main lower portions of the members 14 and 15 constitute divergent legs terminating at their lower ends in inwardly directed spurs 21 adapted to project into the sockets 12 or bushings 13, the main portions of the legs being longer and flexible enough for these spurs to be sprung or snapped into 70 said sockets. When, however, the device is in holding position there is no practical possibility of the picture becoming disconnected therefrom. As shown best in Fig. 4 the spurs 21 are formed by slitting the metal of 80 the legs at 22 forming free edges 23 which are rolled into substantially cylindrical form. As suggested in Figs. 1 and 4 the legs may be shaped and otherwise ornamented to simulate streamers if desired, but with reference 85 to the ornamental appearance I have filed concurrently herewith a design application.

The hollow rivet 16 constitutes, in addition to the means for securing the main or leg portions of the holder together, a means 90 to readily attach any suitable ornament such as indicated at 24. This ornament is provided with a rearwardly extending split shank 25 having a rounded point adapted to be forced through the rivet 16 where it will 95 be held automatically by its resiliency.

When the holder is detached from the picture frame the interlocking joint at 18 may readily be opened and the two portions 17 may be separated at the joint 18 by swinging the leg portions upward from each other slightly and thereafter the device as a whole may be folded with the leg portions in close parallelism for storage or transportation purposes. The ornament 24 obviously may 100 be removed for this purpose by simply slipping it from the hollow rivet 16. For use as an easel the holder may swing bodily as a unit around the horizontal axis of the two spurs so as to bring the head or loop portion 110 thereof down into position to rest upon the table or other support, the spurs still being

held in engagement with the picture frame as already described.

I claim:

In a picture holder, the combination of a pair of leg members, means to pivot said members together scissor fashion between their ends, a pair of coöperating hooks formed at their upper ends to lock said mem-

bers from pivotal movement with respect to each other, and means to connect said leg members to a picture.

ZVETKO ORIZAROFF.
